United States Patent Office.

ELIJAH HUMPHREYS, OF SAMSVILLE, ILLINOIS.

Letters Patent No. 92,451, dated July 13, 1869.

IMPROVEMENT IN FENCE-GATE POST.

The Schedule referred to in these Letters Patent and making part of the same.

To whom it may concern:

Be it known that I, ELIJAH HUMPHREYS, of Sams-ville, in the county of Edwards, and State of Illinois, have, as I believe, invented a new and useful Improvement in Fence-Gate Posts; and I do hereby declare the following to be a full and exact description of the same, reference being had to the drawings that accom-pany and form a part of these specifications.

Figure 1 is a front-view elevation on a line.

Figure 2, side view, with gate attached.

Letter A, upright post which sustains the gate.

Letter B, bed-piece, in which rests the lower end of the post A, and lower inner end of the gate.

Letters C C, lateral braces for the post A, one on each side.

Letter D, brace or anchor-bar, from near the top of post A to the ground, at F.

Letter E, a short brace, acting to prevent the bed-piece from being thrown back by the weight of the gate.

Letter F, the firm ground, where rests the lower end of the brace D, and should be as far from the base of post A as the height of said post, and, if the surround-ings are such as to allow, may be much further.

g, a strong pin through the brace D, at right angles to it, as seen in the drawings.

h h, two posts or stakes, of wood or stone; if of wood, driven into the ground firmly; if of stone, may be driven in the ground, or be of sufficient weight to perform their office without, which office is to hold immovable the lower end of the brace D.

i i, several holes near the end of the brace D, which passes through a mortise, j, in the post A.

k, a pin, which may be placed in any one of the holes i, to adjust the gate.

l, a key for adjusting the brace E to its work.

m m, two keys, which, driven between the blocks h and the pin g, provide a further adjustment of the gate, and one more readily applied, as it is accom-plished simply by driving these keys down or up.

The object of this invention is to provide a conven-ient gate-post, that shall not be constantly getting out of position by the action of frost, or the loosening ef-fects of water in the soil; also, to provide for sustain-ing a gate-post at the spot desired, though there may be, at that place, obstructions to forming a post-hole.

From an examination of the drawings, one will see the bed-piece B and braces C C will be amply suffi-cient for all lateral resistance.

The brace or anchor D retains the upper end of the post A in position, and is adjustable at either end, so that, if the gate should sag, or in case of snows, or when frost would forbid the adjustment of a post set in the ground, any adjustment desirable may be read-ily and at once secured.

By pressing the upper end of the post A back, causing the bar D to extend further through the mortise j, the pin k may be so placed as to raise the outer end of the gate very considerably from the ground; and this might be very desirable in case of deep snows, and the gate could as readily be brought to its normal position, and at times when the point at F might not be accessible on account of snow or ice.

This gate and post will be of great utility in use with a movable fence, as they can be drawn bodily about the field.

This structure is such that small timbers will be sufficient.

The dragging of the outer end, so destructive to a gate, need never occur with this device of mine.

Another great convenience is, that the gate may be set in place in early spring, before the frost would be sufficiently out to allow a hole to be made in the ground.

What I claim as of my invention, and desire to se-serve by Letters Patent, is—

1. The brace D, provided with the gauge-holes i i, and auxiliary brace E, in combination with the post A, substantially as and for the purposes described and set forth.

2. The brace D, provided with the pin g, in combi-nation with the blocks or posts h h and keys m m, as and for the purposes specified.

In testimony whereof, I have signed my name to this specification, in the presence of two subscribing witnesses.

ELIJAH HUMPHREYS.
